CLAIM

The ornamental design for a display screen with graphical user interface, as shown and described.

DESCRIPTION

FIG. 1 is a front view of a display screen showing a first image of a graphical user interface;

FIG. 2 is a front view of a display screen showing a second image of the graphical user interface;

FIG. 3 is a front view of a display screen showing a third image of the graphical user interface;

FIG. 4 is a front view of a display screen showing a fourth image of the graphical user interface;

FIG. 5 is a front view of a display screen showing a fifth image of the graphical user interface;

FIG. 6 is a front view of a display screen showing a sixth image of the graphical user interface;

FIG. 7 is a front view of a display screen showing a seventh image of the graphical user interface;

FIG. 8 is a front view of a display screen showing an eighth image of the graphical user interface;

FIG. 9 is a front view of a display screen showing a ninth image of the graphical user interface; and,

FIG. 10 is a front view of a display screen showing a tenth image of the graphical user interface.

The appearance of the graphical user interface of the display screen transitions between the images shown in FIGS. 1 to 10. The process or period in which the graphical user interface transitions forms no part of the claimed design. The dot-dash broken lines illustrate the display screen and form no part of the claimed design. The remaining broken lines illustrate portions of the graphical user interface that form no part of the claimed design.

1 Claim, 10 Drawing Sheets

FIG. 2

FIG. 3

No SIM 21:02 WOUND Have you experienced any of the following symptoms?

Mild Itching or pain

Intense Itching

Burning sensation

Severe pain

More severe symptoms

Have you seen the insect that bit you?

Bigger than a mosquito

A mosquito size or smaller

I don't know

FIG. 4

FIG. 5

FIG. 6

The image shows a smartphone screen with a survey application. At the top, there are three status icons: 'No SIM!' with a signal strength icon, '21:03' in the center, and a battery icon on the right. Below the status bar is a back arrow icon. The main content area is a survey form. The first section asks, 'What were the characteristics of the place you recently visited?' and lists eight options: 'Indoors', 'Not sure', 'Grassland', 'Near plants', 'Near flowers/bee hives', 'Near water source', 'Near sandy area', 'Dark and damp', 'Contact with animals', and 'Not sure'. Each option is preceded by a radio button. The 'Indoors' and 'Not sure' options are grouped together in a box. The 'Not sure' option is also listed again below the list of characteristics. The 'Submit' button is located at the bottom of the survey form.

Grassland

Near plants

Near flowers/bee hives

Near water source

Near sandy area

Dark and damp

Contact with animals

Not sure

Submitted

Can you upload a picture of the wound?

Upload Skip

FIG. 8

No SIM 21:03 Based on the information you provided, the insect that bit you is most likely a fly. Here are some general tips for treating and preventing fly bites:

Treatment:

- Wash the affected area with soap and water.
- Apply a cold compress to reduce swelling and itching.
- If the itching is severe, you can use over-the-counter anti-itch cream or take an antihistamine.

Prevention:

- Wear long sleeves and pants when spending time in areas with lots of flies.
- Use insect repellent containing DEET or picaridin.
